CLAIM

We claim the ornamental design for a game controller, as shown and described.

DESCRIPTION

FIG. 1 is a top plan view of a game controller showing our new design;

FIG. 2 is a bottom plan view thereof;

FIG. 3 is a left side elevation view thereof;

FIG. 4 is a right side elevation view thereof;

FIG. 5 is a front elevation view thereof;

FIG. 6 is a rear elevation view thereof; and,

FIG. 7 is a perspective view thereof.

1 Claim, 6 Drawing Sheets
